(57) **CLAIM**

The ornamental design for a wireless charger pad for electronic device as shown and described.

DESCRIPTION

FIG. 1 is a front, top, and left side perspective view of a wireless charger pad for electronic device, showing my new design;

FIG. 2 is a front view thereof;

FIG. 3 is a back view thereof;

FIG. 4 is a left-side view thereof;

FIG. 5 is a right-side view thereof;

FIG. 6 is a top view thereof;

FIG. 7 is a bottom view thereof;

FIG. 8 is a rear, bottom, and left side perspective view thereof; and,

FIG. 9 is a rear, top, and left side perspective view thereof in a state of use.

The broken lines shown in FIGS. 1, 3, and 6-9 depict portions of the wireless charger pad for electronic device and form no part of the claimed design. The broken lines representing a wireless charger and wire shown in FIG. 9 depict environment and form no part of the claimed design.

1 Claim, 7 Drawing Sheets
